United States Patent Office

Des. 198,095
Patented Apr. 28, 1964

198,095

CLOCK

Jack K. Champlin, 2327 Market St., San Francisco, Calif.

Filed Dec. 12, 1962, Ser. No. 72,820

Term of patent 14 years

(Cl. D42—7)

Fig. 1

Fig. 2

FIGURE 1 is a front elevational view of a clock showing my new design, it being understood that the grooved ornamentation partially shown thereon is continuous in the paths shown; and

FIGURE 2 is a side elevational view thereof.

I claim:

The ornamental design for a clock, substantially as shown and described.
